SAFETY POCKET

Eliseo Petronio, Cleveland, Ohio

Application March 12, 1932. Serial No. 598,460

3 Claims. (Cl. 2—254)

My invention particularly relates to safety pockets for clothing whereby the loss of coins, keys, bill-folds, and other articles usually carried in the pockets of clothing, is obviated. The object of the invention is to provide simple means furnishing the stated protection which can be economically and easily applied and which will not be cumbersome or mar the appearance of the garment.

10 The annexed drawing and the following description set forth in detail certain means embodying my invention, such disclosed means constituting, however, but two of the various forms in which the principle of the invention may be embodied.

15 In said annexed drawing:

Figure 1 is a fragmentary elevation of the upper right side of a pair of trousers or overalls in upright position, and showing in dotted lines a 20 trousers side pocket embodying one form of my improved safety features, as also certain coins in the pocket;

25 Figures 2 and 3 are horizontal sections, taken, respectively, in the planes indicated by the lines 2—2 and 3—3, Figure 1;

30 Figure 4 is a view similar to Figure 3, showing the several positions of the pocket parts and the coins contained therein, when the garment wearer is in a reclining position;

35 Figure 5 is a vertical section, taken in the plane indicated by the line 5—5, Figure 1;

40 Figure 6 is an elevation of the interior side of the pocket in expanded or flat condition before it is applied to the garment;

45 Figures 7 and 8 are elevations of detached front and rear partition members, respectively, forming parts of the improved safety pocket;

50 Figure 9 is a fragmentary elevation of a garment in normal wearing position and provided with another form of my improved safety pocket, the view also showing a bill-fold in the safety pocket;

55 Figure 10 is a vertical section, taken in the plane indicated by the line 10—10, Figure 9; and

Figure 11 is a view similar to Figure 10, showing the positions of the several elements when the pocket is tilted.

Referring to the annexed drawing in which the same parts are designated by the same respective numbers in the several views, a pair of trousers 1, Figures 1 to 5, is provided with my improved safety pocket 2 which comprises a fabric member 3 of the form, in opened condition, clearly indicated in Figure 6, and two partition flaps 4 and 5, of the form clearly shown in Figures 7

and 8, respectively, which flaps are of irregular four-sided formation and are secured by three side edges to the member 3. The four sides of the front partition 4 are indicated by the numbers 6, 7, 8 and 9, and the side 9 is at the bottom and is the side which is not attached to the member 3. Correspondingly, the four sides of the rear partition 5 are indicated by the numbers 10, 11, 12 and 13 and the side 13 is at the bottom and is the one which is not attached to the member 3.

60 The general shape of the flaps 4 and 5 is the same except that the front flap 4 is deeper than the rear flap 5 along the inside short edge and more shallow along the outside long edge, so that the flap 4 hangs below the flap 5, in the center and

65 is above the flap 5 at the outside edge, as clearly indicated in Figure 6, in the open detached condition of the pocket. However, when the member 3 is folded in the vertical plane bisecting the lower notched area 3' to produce the pocket

70 chamber 14, and the edges 15 and 16 of the member 3 are secured to the bands 17 and 18, respectively, by means of which the pocket is secured, adjacent the pocket opening 19, to the member 3,

75 the flap bottom edges 9 and 13 intersect in a criss-cross fashion, substantially in the center of the pocket, as clearly indicated in Figure 1, the bottom point of the edge 8 lying substantially in the same horizontal plane as the bottom point of the edge 11, so that a symmetrical bottom opening

80 20 between the flaps 4 and 5 is formed, as clearly indicated in Figure 3. It is evident that side openings 21 and 22 are formed between the sides of the folded member 3 and the respective flaps

85 4 and 5, which side openings 21 and 22 provide no means of escape for pocket contents at the top, inasmuch as the edges 6 and 10 of the flaps 4 and 5 are secured to the member 3. It will be

90 noted that these edges 6 and 10 of the flaps 4 and 5 are inclined at substantially a 45° angle and thus conserve considerable material in making the flaps 4 and 5, that portion 23 of the pocket

95 chamber which is thus eliminated as a container for contents being a portion of the pocket chamber which is of no value or use in any event, as will be readily understood. The unattached bottom edges 9 and 13 of the flaps 4 and 5 are formed

100 with a piping to insure a finished edge and to aid in the smooth hanging of the bottom portions of the flaps.

105 The described construction provides means whereby the pocket contents, such as coins 24, will slide upon the inside surface of the member 3 into the closed pockets 21 and 22, when the wearer of the garment 1 is in a reclining position,

as clearly indicated in Figure 4, or when the pocket 2 is tilted for any reason. The flaps 4 and 5 will not adhere to the inner surface of the member 3 and thus direct the pocket contents into the opening 25 between the flaps 4 and 5, but the contents will tend to dish one side of the member 3, as clearly indicated in Figure 4, and increase the size and entrance opening of the pockets 21 and/or 22, and thus facilitate the entry 10 of the pocket contents into the closed chambers. The inclined formation of the flap edges 6 and 10 prevents the pocket contents from entering and becoming locked in an elusive and inaccessible rear top portion of the pocket chamber. 15 The relative sizes of the flaps 4 and 5, and particularly the relative lengths of the edges 8 and 12, and the inclined form of the bottom edges 9 and 13, provide both a symmetrical formation and yet serve to divert the pocket contents into the openings 21 and 22 in a much more effective manner than would be possible with flaps having bottom edges which are aligned and substantially 20 parallel one with the other.

In the form of safety pocket illustrated in Figures 9, 10 and 11, the pocket material 26, intended particularly for a coat or vest pocket having a top opening, is folded so as to provide an auxiliary chamber 28 vertically aligned with and above the normal pocket chamber 27. The pocket material 26 is connected to the coat or other garment 29 so as to form a side opening 30 adjacent the top of the pocket and substantially laterally aligned with the bottom of the auxiliary chamber 28. When the pocket is tilted because of the bending over of the wearer, or for any other reason, the pocket contents such as a letter or a bill-fold 31 will slide into the auxiliary chamber 28, as clearly illustrated in Figure 11, and thus be 35 prevented from falling out of the pocket through the pocket opening 30. There is no difficulty in inserting the contents into the pocket 27 with this construction inasmuch as the depending coat flap 32 and the outside wall 28' of the auxiliary chamber 28 above the pocket opening 30 readily bend 40

inwardly to permit the insertion of the flat pocket package within the chamber 27.

What I claim is:

1. A safety pocket for wearing apparel comprising a folded member secured at its edges to form an article-containing chamber having an ingress and egress opening, and a plurality of depending flaps secured within and to said member and forming an auxiliary chamber between adjacent flaps and side chambers between said flaps and the adjacent inner walls of the folded member, said auxiliary and side chambers having bottom openings communicating with said article-containing chamber, and said side chambers being closed at the top, the bottom edges of said flaps being inclined to induce a crosswise movement of articles in the containing chamber in a tilted position of the pocket, the bottom edges of said flaps for their entire length being free from each other and from the adjacent inner walls of the folded member, and the side edge of each flap adjacent the fold of the folded member being secured to the folded member. 80 85 90 95

2. A safety pocket for wearing apparel comprising a folded member secured at its edges to form an article-containing chamber having an ingress and egress opening, and a pair of spaced depending flaps secured within and to said member and forming an auxiliary chamber between the flaps and side chambers between said flaps and the adjacent inner walls of the folded member, said auxiliary and side chambers having bottom openings communicating with said article-containing chamber, and said side chambers being closed at the sides and top, the bottom edges of said flaps being inclined in opposite directions so as to intersect in criss-cross fashion adjacent the center of the pocket whereby there is induced a crosswise movement of articles in the containing chamber and into the bottom openings of said side chambers in a tilted position of the pocket. 100 105 110 115 120

3. A safety pocket according to claim 1 and in which the upper edges of the flaps are inclined relative to the fold of the folded member.
